UNITED STATES PATENT OFFICE.

VICTOR R. HEFTLER, OF DETROIT, MICHIGAN, ASSIGNOR TO SOCIETE DU CARBURETEUR ZENITH, OF LYON, FRANCE, A CORPORATION OF FRANCE.

CARBURETEUR.

1,255,165.

Specification of Letters Patent. Patented Feb. 5, 1918.

Application filed February 24, 1916. Serial No. 20,282.

To all whom it may concern:

Be it known that I, VICTOR R. HEFTLER, a citizen of the Republic of France, residing at Detroit, county of Wayne, State of Michigan, have invented a certain new and useful Improvement in Carbureters, and declare the following to be a full, clear, and exact description of the same, such as will enable others skilled in the art to which it pertains to make and use the same, reference being had to the accompanying drawings, which form a part of this specification.

This invention relates to improvements in carbureter nozzles, and has for its object the provision of a simple, effective and cheap method of constructing the same. It is capable of embodiment in any one of several different types of carbureters as such, with modifications in detail features only; its advantages in the several respects suggested will appear further from the description.

In the drawings:

Figure 1 is a sectional elevation of my construction as applied to a plain, single-nozzle carbureter.

Fig. 2 is a similar view of my improved construction applied to a compound nozzle carbureter.

A represents a carbureter wall provided with an outlet aperture B, through which there engages a tube C, preferably of brass and provided with a terminal collar or flange D. E is a disk or washer, preferably of hard material having an opening F for the passage of gasolene. This disk is wrapped in an envelop or cushion G of relatively soft material, preferably copper, so made as to engage over the edge and the adjacent peripheral portion of each face of the disk; this wrapping may, if desired, have a cylindrical projection or collar H, whose function is the centering of the disk and its envelop with respect to the axis of the tube C and of the holding nut J, into whose hollow center portion it projects; the holding nut, whether the collar H is employed or not, engages with its screw threaded periphery in the complementary screw threading on the inner face of the carbureter shell. By means of this holding nut the disk E and its relatively soft envelop are forced against the flange D of the tube C, which may if desired, be spaced from the adjacent carbureter wall, the edges of whose aperture

confine myself to the form of envelop or cushion member shown in the drawings, however, although for reasons of economy of manufacture I prefer it to an annular cushion of solder applied to one face of the disk near its edge, and adapted to be flattened by pressure of the nut forcing it against the shoulder in the carbureter shell, or some such similar equivalent. The single gasolene channel, in the form of device illustrated in Fig. 1, is shown at L; and below the holding nut J, though somewhat spaced therefrom, is the threaded plug M, by whose removal access is afforded to the parts already described.

With a construction of this character I am enabled to have the wall of the nozzle proper made very thin, thus making a reduction in its diameter possible, and in turn bringing the action of the aspirating air current about the nozzle so much closer to the vacuum-drawn stream of gasolene emerging from the top of the nozzle. I am furthermore enabled to dispense with a nozzle projecting integrally from the carbureter wall, whose manufacture was a very expensive item, both as regards actual mass of material used and the expensive and delicate drilling of a bore through the projecting blank of metal. In either form of wrapping or cushioning for the perforated disk the measuring or calibrating orifice is provided in the hole F in the disk E, which can be made inexpensively in a punch press from some such relatively hard material as German silver or nickel. This insures a calibrated opening which the friction of the gasolene will wear but very little, and one whose size can be very easily altered by the substitution of one disk or washer for another, the holding nut J with its large central orifice remaining unchanged, and being easily removable when the disk is to be changed. A tight fit is assured because of the screwing up of the holding nut J against the relatively soft envelop G to the desired degree of tightness against the flange B of the tube A.

Fig. 2 shows the application of this idea to a compound nozzle carbureter, in which two gasolene feeds are delivered to concentric nozzles such as shown in the patent to Baverey, No. 997,953. In this form the carbureter wall A is provided with two gasolene outlets N and P, one being in direct connec-

tion with the supply channel L from the float chamber, the other being broken by an atmospheric air well I, to effect compensation and uniformity of mixture at varying engine speeds, now well known in the art. The two nozzle tubes Q and R are arranged one within the other, the lower end of the inner tube R resting in and passing through the centrally bored and peripherally threaded nut O, which adjustably engages in a complementarily threaded portion of the inner face of the carburetor wall A. Nut O which supports the outer tube Q is provided with a hole T by which it is placed in direct communication with the atmospherically exposed gasolene channel P, and the tube Q is preferably, though not necessarily, flanged at its lower end, a washer S being preferably interposed between the flange and the overengaging portion of the shell at the top of the bored passage in which the threaded nut O engages. Just beneath the lower end of the threaded nut O, though appreciably spaced therefrom, is a perforated disk W with its envelop V, similar to the disk E and its envelop G shown in Fig. 1, which preferably rests against a seat on shoulder U in the carburetor shell, and is adapted to be held in position with the required degree of firmness by means of the threaded and centrally apertured holding nut Z, similar to the holding nut J in the construction shown in Fig. 1. The well I receives its fuel through a similar removable disk member W' which is cushioned by the envelop V' and is held in place against the shoulder U' by the similar threaded holding nut Z'; the fuel passes thence through the channel P and hole T in the threaded nut O to the inner nozzle member R. Access to the parts of this type of construction is afforded by removing the threaded plugs Y and Y' at the bottom of the carburetor shell. Through the space which separates the bottom of the threaded nut Z and the top of the plug Y gasolene is drawn from the lower channel N and passes through the calibrated opening in the disk or washer W into its nozzle R.

50 I claim—

1. A carburetor nozzle, having, in combination with the apertured carburetor wall, a tubular member having a flanged end engaging therethrough, a washer member provided with a calibrated aperture engaging across the flanged end of said tubular member, a peripherally overengaging inclosure for said washer, and means for forcing said washer member and its inclosure against the flanged end of said tubular member, thereby forcing the same against the inner face of the carburetor wall.
2. In a carburetor, an apertured shell, a terminally flanged tube extending therethrough, a perforated disk located adjacent the inner

end of said tube, a peripherally arranged cushion for said disk, and means for holding said disk and its cushion in desired relation to the end of said tube and for adjustably forcing the flanged portion of said tube against those portions of the shell which surround the aperture therein. 70

3. In a carburetor nozzle, in combination with a terminally flanged tube adapted to project through the carburetor wall, a perforated disk located interiorly of the flanged inner end of the tube, a peripheral washer for said disk provided with an interiorly extending collar, and a nut adapted to force said disk and its washer against the flange 75 on said tube, thereby forcing the flanged portion of said tube firmly against the inner face of the carburetor wall. 80

4. In combination with a threaded and apertured portion of a carburetor shell, a flanged tube projecting through the aperture with its flanged portion inside of the carburetor shell, a perforated disk, a peripheral envelop therefor located adjacent said flanged portion of the tube, and a centrally apertured nut adapted to engage the threaded portion of the carburetor shell to force the disk and its envelop toward the flanged end of the tube, the flanged portion of the tube being thus held in desired firm relation 90 to the carburetor shell. 95

5. In a carburetor, the combination of a shell provided with inlet and outlet apertures, a perforated disk member adapted to regulate the flow through the outlet aperture, a peripheral cushion member therefor, and adjustable means for holding said disk member and its cushion in close relation to said outlet aperture. 100

6. In a carburetor, in combination with an apertured shell, a terminally flanged tubular outlet member extending therewith, with its flanged portion in engagement with the inner face of the shell adjacent the aperture, a disk member provided with a calibrated aperture located across the inner end of said tubular outlet member, a peripherally engaging envelop member therefor, and an adjustable nut engaging a correspondingly screw-threaded portion of the shell, whereby 115 said disk member and its envelop are held in close relation to the adjacent flanged end of said tubular member, thereby holding the same firmly against the adjacent inner face of the shell. 120

7. In a carburetor, the combination of an apertured shell, a flanged tube projecting therethrough, a perforated disk provided with a relatively soft peripheral envelop engaging the flange on said tube, and adjustable means for forcing the disk and flanged tube into close relation with respect to the aperture in the shell. 125

8. In combination with a carburetor shell provided with an outlet aperture, a nozzle 130

- projecting through the outlet aperture, the flanged inner end of said nozzle engaging against the inner face of the surrounding shell, a perforated regulating member, and 5 means whereby the regulating member may be removably held in position across the path of travel of the gasoline emerging through said nozzle, and against the flanged inner end of said nozzle.
- 10 9. In a carbureter, a shell having a threaded recess provided with inlet and outlet passages and a seat therewithin, a centrally apertured disk, a compressible gasket for said disk, and means for forcing said disk 15 and its gasket against the seat in said recess.
- 10 10. In a carbureter, the combination of a shell having a recess provided with inlet and outlet passages, a centrally apertured disk, a peripheral cushion for said disk having a 20 cylindrical collar projecting from one face thereof, and apertured means for forcing said disk and its envelop into seating position with respect to said outlet passage in the carbureter shell.
- 25 11. In a carbureter, the combination of a tube passing through the shell of the carbureter, its inner end being flanged and engaging over the adjacent portion of the carbureter shell, an apertured disk member adapted to control the flow of fuel from the carbureter through said tube, and an adjustable holding nut whereby said disk member may be held in close relation to the flanged end of said tube.
- 35 12. A carbureter nozzle, having in combination a removable tubular outlet, a disk having a centrally arranged aperture adapted to control the flow of gasoline through said tubular outlet, a peripheral envelop for said disk, and a holding nut whereby the disk and its envelop may be forced into desired proximity to the carbureter shell and to the adjacent end of the tubular outlet.
- 35 13. In a carbureter nozzle, in combination 40 with a shell having a plurality of fuel channels, a plurality of concentrically arranged tubular outlet members, each adapted to serve one of said channels, removable perforated disks adapted to control the flow of gasoline through said outlets, peripheral envelops therefor, and adjustable means for holding each disk and its envelop in desired position with respect to the tubular outlet to which it is apurtenant.
- 35 14. A carbureter nozzle, having in combination with a threaded and apertured portion of the carbureter shell, a centrally apertured and peripherally threaded nut engaging therein, a pair of concentrically arranged outlet tubes, engaging through the carbureter shell, one of said outlet tubes also 45 engaging through the apertured central portion of said threaded nut, and a centrally perforated disk whereby the operative cross-sectional area of one of said tubes is regulated.
15. In a carbureter nozzle, in combination with an apertured portion of the carbureter shell, a pair of concentrically arranged tubes engaging therethrough, an 50 apertured and peripherally cushioned disk controlling the inner end of one of said tubes, and adjustable holding members whereby the tubes may be held in place and whereby each disk may be forced into regulating 55 position with respect to its tube.
16. A carbureter nozzle, having in combination a pair of concentrically arranged tube members, a disk having a calibrated aperture controlling the flow through one of 60 said tubes, a peripheral envelop therefor, a regulating nut adapted to force said washer and its peripheral envelop toward the adjacent end of its tube, and a second nut for holding the other tube in position with respect to the carbureter shell and its companion tube.
17. In combination with a carbureter shell provided with an outlet aperture and having a plurality of gasoline channels leading thereto, a pair of tubular outlet members arranged one within the other passing through said outlet aperture, each of said tubular outlet members being served by a different gasoline channel, and removable 70 cushioned disk members having calibrated apertures whereby the flow through said channels may be regulated.
18. In combination with a carbureter shell provided with a plurality of inlet passages 80 and a single outlet aperture, a pair of centrally arranged tubular outlet members engaging therethrough, centrally apertured disks adapted to regulate the flow through each of said inlet passages, a gasket for each 85 of said disks, and means for forcing said disks and the gasket into controlling position with respect to their respective tubular outlet members.
19. The combination of a carbureter shell 90 provided with a tubular nozzle, a removable perforated disk adapted to control the flow therethrough, a peripheral envelop for said disk, and adjustable means for forcing said disk and its envelop into controlling position with respect to said nozzle.
- In testimony whereof, I sign this specification in the presence of two witnesses.
